[57] **CLAIM**

The ornamental design for an personal flotation device panel, as shown and described.

DESCRIPTION

FIG. 1 is a front view of a personal flotation device panel showing my design;

FIG. 2 is a back view thereof;

FIG. 3 is a side view thereof;

FIG. 4 is a side view thereof opposite to the side shown in FIG. 3;

FIG. 5 is a top view thereof;

FIG. 6 is a bottom view thereof; and,

FIG. 7 is a perspective view thereof shown incorporated into a personal flotation device as a right side front panel member together with another panel of my design that is a mirror image to the panel shown in FIGS. 1-6 which is a left side front panel member.
